(57) **CLAIM**

The ornamental design for a gas storage container, as shown and described.

DESCRIPTION

FIG. 1 is a frontal view of the gas storage container;
FIG. 2 is a rear view of the gas storage container;
FIG. 3 is a left side view of the gas storage container;
FIG. 4 is a right side view of the gas storage container;
FIG. 5 is a top view of the gas storage;
FIG. 6 is a bottom view of the gas storage container;
FIG. 7 is a perspective view of the gas storage container; and,
FIG. 8 is another perspective view of the gas storage container, shown with additional environment.
The broken line showing of a valve portion is for the purpose of illustrating environmental structure and forms no part of the claimed design.

1 Claim, 8 Drawing Sheets
